Cha Conch & James A. Tracy
Locals Patent

The Schedule referred to in their Local Patent and making part
of the same containing a description in the words of Cha Conch
& James A. Tracy themselves of their improvement in Barrels for
suspension called Conch & Tracy's Barrel Lamp

It is known that we Cha Conch & James A. Tracy both of Noroton
in New Haven County, State of Connecticut & both native born citizens
of the United States have invented a new & useful improvement
in Barrels for suspension called "Conch & Tracy's Barrel Lamp"
that the following is a full & exact description of the construction &
operation of the same as invented or improved by us. The body of the
Lamp is a circular barrel in the shape of a hollow circular tube or hoop
about seven inches in diameter from end to end & on the inner
side a little short of four inches. There suspended the horizontal diam-
eter of the hollow circle or tube forming the barrel is about one and a
half inch from outside to outside the perpendicular diameter is about
one quarter of an inch less so that diminishing the thickness of the shell
the hollow of the circular barrel will be a little more than one inch
in diameter extending round an open circle of about four inches in di-
ameter. This circular barrel is designed for the reception of oil & well
hole about one pint extending nearly all round the circle. It is made
of black tin or other suitable material in halves on a circular mould
to the shape of half the circular barrel in two casting, the top & bottom
being alike & are then put ^{made} together so as to form the bar-
rel. On the top of the barrel is inserted a filler tube with a
screw top for supplying the barrel with oil & on the inner circle of the
barrel are inserted four tubes for wicks opening into the circular barrel
about $1\frac{1}{2}$ of an inch & rising about 15 $\frac{1}{2}$ inch inclining towards the center
in an angle of about 20 degrees leaving an open space between the wicks
of about two inches or more. There also are of tin added a pair
of

57483X

into the circular barrel on the inner side of the side rock forming an opening for rock about one-half broad & $\frac{1}{8}$ of an inch thick with suitable openings on the outer side for rock, covering the rock on the outside of the circular barrel and have at equal distances three wells or holes in each about $3\frac{1}{2}$ inches long by which the lamp may be suspended. Over the barrel lamp has made, when suspended a globe of glass or glass resting on the barrel to give a double edge of rock from the inside & about that terminating the rock there is a bright tin reflector supported by the suspending chains in the usual manner. The advantage of this mode of constructing the lamp over any other heretofore invented are that the mass of oil is brought near the edge of the rock & they will therefore continue to burn freely while the whole is suspended. The surface of the circular opening is enlarged so the downward light is less interrupted than in any other and is thereby increased by the full force of the reflector. We do not claim as our invention the central opening merely for a downward light that has long been known and used, but we do claim as our invention the circular barrel as above specified & described & the use of same for construction of the lamp as above described, forming a lamp upon a new construction wholly other & superior to any other now or ever more especially when a downward light is required & for this they submit to your Patent Office. In testimony whereof we have hereunto set our hands and signatures this 10th day of February A.D. 1833
